PORTABLE MICROFICHE VIEWER

Paul B. Specht, Evanston, and Alan N. Taylor, Skokie,
Ill., assignors to Library Resources Inc., Chicago, Ill.

Filed Mar. 18, 1971, Ser. No. 125,915

Term of patent 14 years

Int. Cl. D16—02

U.S. Cl. D61—1

FIG. 1 is a front elevational view of a portable microfiche viewer showing our new design;

FIG. 2 is a top plan view thereof;

FIG. 3 is a bottom plan view thereof on a reduced scale;

FIG. 4 is a left side elevational view thereof;

FIG. 5 is a right side elevational view thereof;

FIG. 6 is a rear elevational view thereof.

We claim:

The ornamental design for a portable microfiche viewer, as shown.
